UNITED STATES PATENT OFFICE.

GEORGE A. RIES, OF OAKLAND, CALIFORNIA.

DESIGN FOR A TOY SUBMARINE.

51,541.

Specification for Design.

Patented Dec. 4, 1917.

Application filed October 11, 1917. Serial No. 196,082. Term of patent 7 years.

To all whom it may concern:

Be it known that I, GEORGE A. RIES, a citizen of the United States of America, residing at Oakland, in the county of Alameda, State of California, have invented a new, original, and ornamental Design for a Toy Submarine, of which the following is a specification, reference being had to the accompanying drawing, in which—

The figure is a view in perspective of the device showing my new design.

I claim:

The ornamental design for a toy submarine, as shown.

GEORGE A. RIES.

Witnesses:

H. H. BAYLISS,
L. A. CRUZ.
